[57] **CLAIM**

The ornamental design for a valve handle, as shown.

DESCRIPTION

FIG. 1 is a top plan view of a valve handle embodying my new design;

FIG. 2 is a side elevational view thereof;

FIG. 3 is another side elevational view taken 90° from that of FIG. 2;

FIG. 4 is a side elevational view taken from the side opposite that shown in FIG. 2; and

FIG. 5 is a bottom plan view.
